UNITED STATES PATENT OFFICE.

FRED W. H. DE VRIES, OF NEAR SALEM, OREGON.

BIT.

1,146,479.

Specification of Letters Patent. Patented July 13, 1915.

Application filed February 18, 1913. Serial No. 749,288.

To all whom it may concern:

Be it known that I, FRED W. H. DE VRIES, a citizen of the United States, residing near Salem, in the county of Marion and State 5 of Oregon, have invented a new and useful Bit, of which the following is a specification.

The present invention is directed to improvements in bridle bits, and has for its object to so construct an article of this character 10 that a medicant can be placed therein for treating horses having the heaves or like ailment.

A further object of the invention is to so construct a bit of this character that can be 15 readily filled with medicant.

With these and other objects in view, this invention resides in the novel features of construction, formation, combination and arrangement of parts to be hereinafter more 20 fully described, claimed and illustrated in the accompanying drawing, in which:—

Figure 1 is a perspective view of the device. Fig. 2 is a longitudinal sectional view therethrough. Fig. 3 is a vertical sectional view 25 through the supporting loop.

Referring to the drawing, the numeral 1 designates the bit, which is tubular and has welded in one end a plug 2 which terminates 30 in an eye 3 for pivotally connecting the ring 4. Upon the other end of the bit 1 is detachably connected a cap 5 which is readily removable so that a medicant can be placed in the bit. Suitably connected to the bit 1, and adjacent the capped end thereof is a 35 clip 6 to which is pivotally connected the arms of the loop 7, said loop serving in con-

junction with the ring 4 to connect the usual check lines. Formed preferably in the center of the bit 1 is a perforation 8, which registers with a perforation 9, which is 40 formed in the bit and diametrically opposite the perforation 8, and serves as a vent, while the perforation 8 permits the medicant to flow from the bit into the horse's mouth. Further it will be noted that if desired the 45 cap 5 can be removed so that a complete circulation of air can be had through the bit so as to keep the same cool in incidents where the bit is used with horses having tender mouths.

From the foregoing description it will be seen that a bit has been provided which can be manufactured at a very small cost, and one which will apply a medicant to the horse's mouth.

What is claimed is:—

A bit of the class described comprising a hollow body having one end closed by a plug, said plug terminating in an eye, a ring pivotally connected to the eye, said body 60 having a cap removably connected to its other end, a loop pivotally connected to said end, said body having registering perforations formed therein between its ends, whereby a medicant contained in the body can be 65 fed through the perforations, as and for the purpose set forth.

FRED DE VRIES.
